US0D1109087S

(12) **United States Design Patent** (10) **Patent No.:** **US D1,109,087 S**
(45) **Date of Patent:** **** Jan. 13, 2026**

(54) **WIRELESS CHARGING STATION**

(71) Applicant: **Shenzhen Puyi Technology Co., Ltd.**,
Shenzhen (CN)

(72) Inventor: **Zhixing Dong**, Changzhi (CN)

(73) Assignee: **Shenzhen Puyi Technology Co., Ltd.**,
Shenzhen (CN)

(**) Term: **15 Years**

(21) Appl. No.: **29/971,430**

(22) Filed: **Nov. 4, 2024**

(51) LOC (15) Cl. **13-02**

(52) U.S. Cl.

USPC **D13/108**

(57) **CLAIM**

The ornamental design for a wireless charging station, as shown and described.

DESCRIPTION

FIG. 1 is a front perspective view of a wireless charging station, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a perspective view showing the wireless charging station in a use state.

The broken lines in the drawings illustrate the portions of the wireless charging station, which form no part of the claimed design.

1 Claim, 9 Drawing Sheets
